UNITED STATES PATENT OFFICE.

VICTOR C. THORNE, OF NEW YORK, N. Y., ASSIGNOR, BY MESNE ASSIGNMENTS, TO THE COLD LIGHT MANUFACTURING COMPANY, INC., A CORPORATION OF COLORADO.

LUMINOUS INDICATING DEVICE.

1,342,778.

Specification of Letters Patent.

Patented June 8, 1920.

Application filed March 16, 1917. Serial No. 155,168.

To all whom it may concern:

Be it known that I, VICTOR C. THORNE, a citizen of the United States of America, residing in the county, city, and State of New York, have invented certain new and useful Improvements in Luminous Indicating Devices, of which the following is a full, clear, and exact description.

The present invention is a form of the 10 luminous indicating device and appliance shown and claimed in my pending application Serial No. 146,644 filed February 5th, 1917. The purpose of the present invention is to provide simple and ready forms of 15 luminous indicating devices and appliance for carrying the device so that they may be united by slight pressure.

Figure 1 represents a switch plate having thereon the usual "on" and "off" switch buttons and provided with the appliance and device attached to the securing means. Fig. 2 a cross-section of a plate with the appliance and device secured to the retaining screw. Fig. 3 a cross section through the 25 appliance and an end view of the device. Fig. 4 a cross section of the preferred form of indicating device. Fig. 5 a top view of the device. Fig. 6 a top view of a modification of the appliance with the device in place. Fig. 7 a cross section through Fig. 6. Fig. 8 a receptacle for holding the device formed directly in the object to be indicated.

The luminous indicating device 1 is in the form of a button and consists of a thin plate 2 of metal preferably brass having a luminous material 8 secured thereto in any preferred manner. The carrier 3 for the indicating device consists of a plate 4 of metal also preferably brass having a flange 5 thereon thereby forming a receptacle 6 for the indicating device. The distance across the carrier at the flange is smaller than the distance across the indicating device, approximately three one-thousandths of an 35 inch, so that the indicating device may be snapped under the flange and into the receptacle 6. By making the plate 2 and the flange 5 of thin metal the indicating device may be readily snapped into the receptacle. 40 To secure the indicating device under the flange, one edge of the device is first placed under the flange and then snapped into the receptacle by slight pressure thereon. When

the indicating device is in the receptacle 6 the flange 5 forms an abutment against its removal.

It is however not necessary that both the plate 2 and flange 5 be flexible the same effect may be obtained by making either of them so.

I prefer to make the indicating device with a flange 7 thereon. The luminous material 8 is secured to one face of a translucent material like celluloid 9. The celluloid is placed on the plate 2 with its uncovered side out, the light rays being visible therethrough. I also prefer to form the celluloid with a convex outer face. This is accomplished by cutting the celluloid slightly larger than the size of the plate, 70 placing it under the flange in a convex form and then pressing the flange 7 down over the celluloid.

The entire indicating device is preferably curved as shown in Fig. 4, so that it may 75 be readily pressed into the receptacle 6 and give a more attractive appearance.

In a modification shown in Figs. 6 and 7, the flange 5^b on the carrier plate 4 is slightly curved inwardly. An annular ring 10 with 80 inclined sides 11 and provided with a flange 12, is pressed against the curved flange 5^b and fits closely thereunder, the bottom of the inclined sides binding against the flange 5^b. An indicating device is snapped under 85 the flange 12 which holds the indicating device in place. Instead of snapping the indicating device under the flange it may first be placed in the receptacle 6 and the ring 10 then pressed into its position.

Any suitable means may be provided for securing the carrier to the object to be indicated. The drawing shows a hole in the plate 4 through which a screw or other securing means are passed wherewith the 95 plate may be secured and then the indicating device snapped into the receptacle. The receptacle may be formed directly in the object to be indicated as shown in Fig. 8, an abutment 5^a being formed therein and the device 100 snapped thereunder. In this figure the walls and abutment of the object are stiff but the spring of the device is sufficient to allow it being snapped under the abutment.

The wall of the receptacle is provided 105 with a perforation 13 which leads under

the plate and permits access to the underside of the device with a pin or other instrument for the removal of the device.

A modification for utilizing the flexibility of the button to secure it in a recess may be practised by first arching the button 1 by pressure so that it is smaller across than the width of the mouth of the receptacle 6. The button 1 is then dropped into the receptacle and is extended to substantially its original shape by pressure, with a blunt instrument, applied to the face 9 of the button whereby it is made wider across than the mouth of the receptacle and is firmly retained therein.

In the appended claims when I speak of the button being secured in the recess by the flexion thereof, I intend to include the methods set out whereby the button is bound in place by taking advantage of the flexibility of the parts.

What I claim is:

1. In combination in a luminous indicating device a button comprising a thin flexible base, walls upturned from said base forming a cup shaped receptacle, a luminous material in the receptacle, a translucent covering over the luminous material the whole forming a unitary, flexible device, an object 30 to be indicated having a recess therein, the

button being secured in the recess by the flexion thereof.

2. In combination in a luminous indicating device a button comprising a thin flexible receptacle, a luminous material in the receptacle, a translucent covering over the luminous material the whole forming a unitary, flexible device, an object to be indicated, a recess therein, the button being normally larger than the mouth of the receptacle, the receptacle being secured in the recess by flexing it through the mouth thereof.

3. In combination an object to be indicated a recess therein and an abutment in the inner walls of said recess, a luminous button comprising a thin flexible base, walls upturned from said base forming a cup shaped receptacle, a luminous material in the receptacle, a translucent covering over the luminous material, the button being a separate and unitary device, said button having flexion and being secured in the recess by snapping it against the abutment and being retained in position in the recess by the abutment.

In witness whereof I have hereunto set my hand.

VICTOR C. THORNE.
